[57] CLAIM

The ornamental design for a bottle clip, as shown and described.

DESCRIPTION

FIG. 1 is a perspective view of a bottle clip, embodying my new design;

FIG. 2 is a top view thereof;

FIG. 3 is a side elevational view thereof, the opposite elevational view thereof being a mirror image; and,

FIG. 4 is a front elevational view thereof, the back elevational view thereof being a mirror image.

The surface in of the claimed design not shown in the drawings or described in the specification form no part thereof.

The broken line showing of a container is for illustrative purposes only and forms no part of the claimed design.
